UNITED STATES PATENT OFFICE

149,001

DESIGN FOR A KITE

Sandy Lang, Chicago, Ill.

Application November 14, 1946, Serial No. 134,788

Term of patent 14 years

(Cl. D34—15)

To all whom it may concern:

Be it known that I, Sandy Lang, a citizen of the United States, residing at 6907 South Perry Avenue, Chicago, Illinois, have invented a new, original, and ornamental Design for a Kite, of which the following is a specification, reference being had to the accompanying drawings, forming a part thereof.

Referring to the drawings, Fig. 1 is a top plan view of a kite embodying my new design; Fig. 2 is a bottom plan view; Fig. 3 is a front elevational view; Fig. 4 is a side elevational view and Fig. 5 is a rear elevational view of the same.

I claim:

The ornamental design for a kite, substantially as shown.

SANDY LANG.
